UNITED STATES PATENT OFFICE.

JOHN M. ROAN, OF COLUMBUS, OHIO.

GATHERING-LOCOMOTIVE.

No. 851,837.

Specification of Letters Patent.

Patented April 30, 1907.

Application filed December 4, 1905. Serial No. 290,146.

To all whom it may concern:

Be it known that I, JOHN M. ROAN, a citizen of the United States, residing at Columbus, in the county of Franklin and State of Ohio, have invented certain new and useful Improvements in Gathering-Locomotives, of which the following is a specification.

This invention relates to new and useful improvements in gathering locomotives for mining purposes.

The object of the invention is to provide a locomotive of the type set forth, having means for gathering mine cars from the various entries and drawing the same into the main entry, so that they may be readily and expeditiously assembled in a train.

Another feature resides in mechanism whereby the gathering means may be thrown into and out of operation, while still another point of novelty lies in clutch means whereby the motor may be operated during the travel of the locomotive or when the same is at rest, thus permitting the gathering means to be operated independently of the locomotive and by the same motor.

Finally the object of the invention is to provide a device of the character described that will be strong, durable and efficient and one in which the several parts will not be liable to get out of working order.

With the above and other objects in view, the invention consists of the novel details of construction and operation, a preferable embodiment of which is described in the specification and illustrated in the accompanying drawings, in which—

Figure 1 is a side elevation of the locomotive showing my invention applied thereto. Fig. 2 is a plan view of the same, showing some of the parts in dotted lines. Fig. 3 is a longitudinal vertical sectional view taken on the line $x-x$ of Fig. 2. Fig. 4 is a rear elevation of the locomotive. Fig. 5 is a cross sectional view taken on the line $y-y$ of Fig. 3. Fig. 6 is a transverse vertical sectional view taken on the line $a-a$ of Fig. 2, the locomotive wheels being omitted. Fig. 7 is a partial longitudinal vertical sectional view taken on the line $b-b$ of Fig. 6. Fig. 8 is a detail elevation of one of the clutch raising arms and its cam, part of said arm being shown in section, and, Fig. 9 is a detail elevation of the drum clutch members and a portion of the shaft.

In the drawings the numeral 1 designates

the usual frame or body of the locomotive, 55 which is supported in the usual manner on flanged wheels 2 at its central portion. At the center of the locomotive a suitable motor 3 is provided at each side of which trolleys 4 are disposed. The motor is incased in a suitable housing 5 which provides bearings for the armature shaft 6, the latter being disposed longitudinally of the locomotive. At the rear end of the body or frame of the locomotive, a suitable controller 7 for the motor 65 is arranged adjacent to the engineer's seat 8.

At its forward end the locomotive carries a vertical fixed shaft 9 on the upper end of which is arranged the usual spring actuated electric cable reel 10. This reel carries the 70 electric cable 11, which passes along one side of the car through suitable guides 12. This cable and reel as will be understood are provided to supply current to the motor, when the locomotive is run off the main trolley 75 line. The reel 10 is rotatably supported on the upper side of a table 13 which is suitably supported above the locomotive body as shown in the drawings. When the electric cable is withdrawn from the reel 10, a 80 spring, not shown, is placed under tension in the same manner that a shade roller is placed under tension when the shade is drawn down. When the cable is released, this spring acts to rotate the reel and rewind the cable thereon. Such a drum is old in this art, and requires no further description. At one side of the locomotive the usual transmission gear 14 shown in dotted lines in Fig. 2, is provided. 85 By means of this transmission gear, the locomotive may be run either backward or forward. The housing 5 of the motor is extended rearwardly so as to form a casing 5^a in which is arranged a transverse shaft 15 as best shown in Fig. 6. On its end the shaft 90 carries a pinion 16 which meshes with the transmission gear 14. The parts so far described are common in the art and are not claimed as new and novel.

Heretofore the motor has of course been 100 suitably connected with the shaft 15 so as to drive the same and thus propel the locomotive. However, no provision has been made for allowing the motor and its armature shaft 6 to operate without propelling 105 the locomotive. The reason for this will be more apparent when it is considered that the gathering means has generally been driven

by a separate motor. The construction which I am about to describe greatly simplifies the locomotive and permits the use of a single motor for all purposes. In the side of the casing 5^a a bearing sleeve 17 is inserted and supports one end of the shaft. A beveled gear 18 as best shown in Fig. 6 is loosely mounted on the shaft and is formed with an extension 19 projecting into the sleeve 17. The beveled gear 18 meshes with a beveled pinion 20 carried on the rear end of the armature shaft 6 as shown in Fig. 3 and in dotted lines in Fig. 2. The motor and the beveled gear are thus permanently connected so that the said gear is caused to revolve when the motor is in operation and it will be apparent that the said gear may be revolved without revolving the shaft 15 and its pinion 16, thus permitting the motor to operate when the locomotive is at rest. For imparting motion to the said shaft and pinion and the transmission gear 14, I provide on the shaft 15 an annular clutch member 21 which while mounted to slide on said shaft, is caused to turn therewith by a key 22 as shown in Fig. 6. The clutch member is suitably formed to engage projections 23 on the beveled gear 18 so that when the said member is moved toward the gear, it will engage with the said projections and thus transmit motion to the shaft. For operating the clutch member, I provide on the same an ordinary split ring 24 (see Figs. 3 and 6) which is arranged in the usual manner to allow the clutch member to revolve, while it is held against movement by arms 25 to the outer ends of which it is pivotally connected. The arms are fixed upon a vertical shaft 26 supported in the casing 5^a and projecting a short distance above the same. For rocking this shaft and swinging the arms to move the clutch member into and out of engagement with the gear 18, I provide a horizontal hand lever 27 keyed on the upper end of the shaft 26. On the underside of the hand lever a spring pawl 28 is provided and arranged to be engaged with a toothed locking segment 29 fixed on the upper side of the casing 5^a. By this means the clutch member may be held in the position to which it is moved.

I will now proceed to describe the gathering means and its various parts. About the shaft 9 at the forward end of the body 1 and below the table 13, a spool or drum 30 is loosely mounted so as to revolve and to be capable of vertical movement. A suitable wire cable 31 is carried by the drum and adapted to have its free end connected with the cars which are to be gathered. At the end and sides of the platform, rollers 32 are provided over which the cable is adapted to pass. These rollers act to assist the winding and unwinding of the cable and prevent the same from dragging over the edges of the car body, thus prolonging the life of the same.

By provision of the side rollers, the cable is supported and guided when cars are being gathered from side entries or entries extending at an angle to the main entry in which the locomotive is traveling. The underside and the center portion of the drum is recessed as indicated at 33, while at its center the drum is provided with a hub 34 by which it is supported on the shaft 9. The lower end of the hub which terminates flush with the lower end of the drum, is supported on the upper end of the clutch portion 36 of a horizontally disposed gear 35 loosely mounted about the lower end of the shaft 9. A vertically movable clutch member 37 is loosely mounted about the sleeve 34 and the upper end of the clutch portion 36. The clutch member 37 is caused to turn with the sleeve 34 and consequently the drum 30, by a key 38 as best shown in Fig. 3. The clutch member 37 is provided with a vertical groove 39, so that it may be freely raised and lowered. In the position shown in Fig. 3, the clutch member 37 is in engagement with the clutch portion 36 of the gear 35, so that motion is being transmitted from the said gear to the drum. For raising and lowering the said clutch member, a split ring 40 is loosely engaged therewith and formed on opposite sides with trunnions 41. These trunnions are pivotally engaged by horizontal arms 42 which are fixed upon a transverse rock shaft 43 disposed between the drum and the gear 35. At one side a crank arm 44 is fixed to the shaft 43 and connected at its upper end to a rod 45. This rod 45 extends rearwardly along one side of the motor housing and casing to a hand lever 46, which is pivoted to one side of the casing 5^a in front of the engineer's seat 8. The lever is formed along its shank portion with an inclined tooth 47 arranged to engage a rack bar 48 mounted on the inner side of a standard 49. The lever 46 is formed of comparatively thin metal so as to be sprung aside to permit its tooth 47 to be moved over the rack bar 48 for the purpose of locking the said lever in its various positions. When the lever is swung forward, the crank arm 44 will be moved rearwardly, thus rocking the shaft 43. The shaft so rocked will swing the arms 42 upward, thereby raising the clutch member 37 out of engagement with the clutch portion 36 of the gear wheel 35, leaving the drum free to revolve so that the cable may be unwound therefrom. With the parts so positioned, the lever 46 will be in its central or intermediate position and by throwing the lever still farther forward, the crank arm will be moved or swung still farther rearward and downward, so that the arms 42 will be swung still higher. On the hub portions of the arms and directly over the shaft 43, cams 50 are secured and engaged with the lower side of the drum 30 so that when the lever is moved

to the last position, the drum will be raised by these cams, so that its upper side firmly engages with a brake ring 51 mounted on the underside of the table 13. This ring is preferably formed of a soft material, so as to have a frictional face with which the drum will engage. By this means the unwinding of the cable from the drum may be governed and the revolution of the drum controlled so that should a car at the end of the cable 31 be running down an incline, it may be stopped when desired by simply moving the drum into contact with the brake ring.

For driving the gear 35 instead of providing an additional motor, I provide the following means for driving the gear by the propelling motor 3. The armature shaft 6 which is extended forwardly in the housing 5, carries at its forward end a beveled pinion 52 which meshes with the beveled gear 53 mounted on the end of a short vertical shaft 54. The shaft is mounted to freely revolve in a flanged bushing 55 which is supported in the sleeve 56 supported upon an annular plan 57 in which the gear 35 is arranged. At its lower end the shaft 54 is provided with a pinion 58 which meshes with the gear 35.

From the description so far as set forth, it will be obvious that when the motor is in motion, both the gear 35 and the gear 18 will be constantly revolved, and that by manipulating the lever 46, the clutch member 37 is engaged with the gear 35 and the drum 30 caused to revolve and wind the cable 31 thereon; while by swinging the hand lever 27, the clutch member 21 may be engaged with the gear 18 to transmit motion to the transmission gear and propel the locomotive. These clutch mechanisms being independent in a sense, they are still dependent as they are both associated with and driven by the same motor.

It is obvious that some means for controlling the locomotive and cars which are being gathered on down grades, must be provided. For this purpose, I provide a brake shoe 59 adapted to bear on the periphery or tire of one of the car wheels 2. The brake shoe is pivotally supported by the standard 49 as shown at 60 in Fig. 1. The brake shoe 59 is engaged by a screw 61 supported in bearing bosses 62 arranged on the upper end of the standard 49. The screw is disposed longitudinally of the locomotive and carries on its rear end a hand wheel 63 adjacent to the engineer's seat 8, so that he may readily manipulate the brake. It will be obvious that when the hand wheel is turned to carry the screw inward, the same impinging against the brake shoe 59, will cause the latter to bind on the wheel, thus checking the travel of the locomotive. It will also be apparent that by increasing the pressure of the screw on the brake shoe, the wheel may be locked against movement and the locomotive thus

held stationary. The locomotive when so held becomes a fixed point, to which the cars may be drawn or gathered. The pressure of the brake shoe on the wheel 2 is of course readily relieved by turning the hand wheel 70 63 in the opposite direction to carry the screw backward, so that the brake may be used in the ordinary manner for controlling the locomotive.

For lowering a car or cars attached to the cable 31 down grade by permitting the drum 30 to revolve and the cable to unwind therefrom, I provide a band brake on the gear 18. The brake comprises an annular outstanding flange 64 projecting from the flat side of the gear as best shown in Figs. 6 and 7. A flexible metallic band 65 is engaged about the flange and carries a plurality of brake shoes or blocks 66 which engage with said flange. One end of the band 65 is secured to the inner side of the casing 5^a as indicated at 67, while the other end of the band is passed through the casing and is pivotally connected to the lower portion of a band brake lever 68 above its pivot point. The brake lever is pivoted at its lower end to the casing 5^a as indicated at 69. When the brake lever 68 is swung rearwardly or away from the casing 5^a, the brake shoes 66 are drawn into close contact by means of the band 65 with the flange 64, and thus the degree of pressure may be readily controlled by the hand lever 68. It is to be understood that when a car or cars are being lowered down grade, the current is cut off from the motor and the clutch member 37 is in engagement with the clutch portion 36 of the gear 35, in which position the lever 46 will stand as shown in Fig.

1. The weight exerted by the cars on the cable, will of course readily unwind the same from the drum and revolve the latter, which in turn will revolve the gear 35 and the armature shaft 6 through the connections therewith. The armature shaft 6 being connected with the gear 18 by the pinion 15, it is readily apparent that by swinging the hand lever 68 rearwardly, the brake is applied and the revolution of the parts checked and controlled. In this manner the unwinding of the cable from the drum 30 is at all times under control of the engineer, so that he may lower the cars down the grade as desired and stop them at any point. It is obvious that the cable may be readily rewound and the cars drawn up the grade if desired by simply switching on the current so as to start the motor in operation, and throwing the lever 68 forward to relieve the pressure of the band brake on the flange 64. When a car or cars have been drawn to the locomotive they may either be coupled thereto, or the drum 30 may be raised into contact with the brake shoe 51 by the lever 46 and cams 50, so that the said drum is held against rotation and the cable prevented

from unwinding. With the parts in this condition, the cars may be drawn along to any desired point.

What I claim, is:

- 5 1. In a gathering locomotive, a motor, means for transmitting motion from the motor to the locomotive, a drum, a cable carried by the drum adapted to be attached to a car, means for transmitting motion from the motor to the drum, and means for disconnecting the transmitting means from the motor without stopping the motor.
- 10 2. In a gathering locomotive, a motor for propelling the locomotive, a drum arranged to be operated by the motor, a cable carried by the drum adapted to be attached to a car, clutch mechanism interposed between the motor and the drum, and means for manipulating the clutch mechanism to connect and disconnect the parts thereof for transmitting motion from the motor to the drum and for permitting the drum to revolve independent of the motor.
- 15 3. In a gathering locomotive, a motor for propelling the locomotive, a drum arranged to be operated by the motor, a cable carried by the drum adapted to be attached to a car, clutch mechanism interposed between the motor and the drum, and means for manipulating the clutch mechanism to connect and
- 20
- 25
- 30

disconnect the parts thereof for transmitting motion from the motor to the drum, said manipulating means also being arranged to move said drum, and a brake adapted to be engaged by said drum when the latter is moved.

4. In a gathering locomotive, a motor for propelling said locomotive, a drum arranged to be operated by said motor, a cable carried by said drum adapted to be attached to a car, means for interrupting the transmission of motion from the motor to the drum to permit the latter to rotate freely, and means for controlling the rotation of the drum.

5. In a gathering locomotive, a motor for propelling said locomotive, a drum adapted to be revolved by the motor, a cable carried by the drum adapted to be attached to a car, means for transmitting motion from the motor to the locomotive, clutch mechanism associated with said transmission means, clutch mechanism interposed between said motor and the drum, a brake for said drum, and a brake for controlling the locomotive.

In testimony whereof I affix my signature in presence of two witnesses.

JOHN M. ROAN.

Witnesses:

A. L. PHELPS,
M. B. SCHLEY.
